UNITED STATES PATENT OFFICE

2,593,041

MACHINE FOR THE MANUFACTURE OF
RUN-RESISTANT KNITTED FABRIC

John Edward Lynam, Mapperly, and Leonard Brown, Nottingham, England, assignors to William Cotton Limited, Loughborough, England

Application August 13, 1948, Serial No. 44,184
In Great Britain August 21, 1947

8 Claims. (Cl. 66—82)

1

In the manufacture of run-resistant knitted fabric by the method forming the subject of British Letters Patent No. 527,234 and United States Patent No. 2,312,903 two sets of bearded needles are employed, those of one set being located immediately to the rear of (i. e. at the bearded side of) but slightly lower than those of the other. At one phase in the knitting sequence it is necessary for the lower needles to be forced towards the front of the machine so that their heads are buried in eyes or grooves in the stems of the upper needles with the result that the lower needles may then be caused to transfix loops that encircle the stems of the upper needles (for example by giving both sets of needles an upward movement which causes these loops to slide down the stems of the upper needles, onto the buried heads of the lower needles). An object of the present invention is the provision of mechanism for effecting this deflection of the lower needles.

Particularly in the method of manufacturing of fabric described with reference to Figures 18 to 26 of the specifications of the two patents above mentioned, it is not practicable in a straight bar knitting machine to employ the normal press edge to deflect the lower needles towards the upper needles, for the press edge occupies too high a level. Extensive experiments have also proved that it is not practicable to employ the edge of the knocking over bar for this purpose either. The somewhat complicated knitting movements necessitate the knocking over bits being provided with holding down throats and being advanced at certain phases to tension or hold down the loops, but at the phase under consideration it is desirable that the knocking over bar and its bits should be retracted so as to avoid tensioning the loops while they are being transfixed by the lower needles.

Therefore according to the present invention a Cotton's patent or other straight bar knitting machine organised for the production of run-resistant fabric by the method forming the subject matter of the aforesaid patents, is provided with a needle-deflecting device, additional to the press edge and the knocking over bar, for producing such needle deflection as will result in the heads of the lower needles being buried in the eyes of the upper needles. This device is best located below the knocking over bar and at the rear (or bearded side) of the needles to engage and deflect the lower needles. It may also operate as a guide for ensuring accurate register of

2

the heads of the lower needles with the eyes of the upper needles.

The above and other features of the invention are set forth in the appended claims and are disclosed in the detailed description, given by way of example, of the particular embodiments illustrated in the accompanying drawings in which:

Figure 1 and Figure 1a constitute a general cross sectional view of a Cotton's patent machine according to this invention.

Figure 2 is a somewhat diagrammatical front view on a smaller scale of Figure 1 illustrating one division of the machine.

Figure 3 is a view of one needle bar and associated mechanism for actuating it.

Figure 4 is a view of the other needle bar and its associated actuating mechanism.

Figure 5 is a view of Figures 3 and 4 combined.

Figure 6 is a view of a catch bar and its associated actuating mechanism.

Figure 7 is a view of mechanism for actuating knocking over bits.

Figure 8 is a view of mechanism for actuating jack springs.

Figure 9 is a view of mechanism for actuating an auxiliary presser.

Figures 10 to 21 illustrate various steps in the movements of needles, sinkers, and knocking over bits in the production of ladder-resistant fabric of the type referred to.

Figure 22 and Figure 22a constitute a detail front elevational view of part of the said machine.

Figure 23 is a plan view of Figure 22.

Figure 24 is an enlargement of part of Figure 23, and

Figure 25 is a cross sectional view of Figure 24.

Figure 26 is a view looking in the direction of the arrow X in Figure 5 illustrating mechanism for actuating both needle bars.

Figure 27 is a diagrammatical illustration showing the arrangement of slur cocks for a multidivision machine.

Figure 28 is a front detail view of the auxiliary presser and associated mechanism.

Figure 29 is a cross sectional view of part of Figure 28.

Figure 30 is a detail perspective view of part of the presser.

The machine illustrated by way of example is that described in the specification of patent application Serial Number 24,354 and is especially applicable to machines for the production of the fashioned blanks of ladies' stockings.

Referring now to Figures 1, 2, 10 to 21, it will be seen that there is provided a set of upper

needles 1, of the customary bearded type, a set of lower needles 2 also of the customary bearded type, customary sinkers 3 and knocking over bits 4. For the purpose of producing ladder-resistant fabric of the type referred to by means of these instruments they are arranged to be manipulated as illustrated in Figures 10 to 21. Of these figures, Figure 10 illustrates a stage whereat the normal draw has taken place so as to sink a new yarn *a* around and between the shanks of needles 1 at a level above the beards of needles 2. The last knitted loops of the fabric are indicated at *b*. Following this stage the needles 1 are lowered in the customary manner as shown in Figure 11 so that the beards of the needles 1 are pressed by presser 6, and the new loops *a* are drawn through the old loops *b* as shown in Figure 12. Both sets of needles then commence to rise again and as shown in Figure 13 the needles 2 are pressed by an auxiliary presser 5 (which constitutes a needle deflecting device according to this invention and which is to be described more fully hereinafter) in such manner that their tips are buried in grooves in the needles 1, the result being (as shown in Figures 14) that the last formed loops *a* are pierced by the needles 2. Figure 15 illustrates the next draw whereat a new yarn *c* is sunk around the shanks of both needles 1 and 2. Both sets of needles are next lowered and during such movement as shown in Figure 16 the beards of the needles 2 are pressed by the customary presser 6 at a stage whereat the points of their beards are disposed between the new loops *c* and the old loops *a* but the said old loops *a* instead of being cast off the needles altogether are knocked over onto the shanks of the needles 1. Both sets of needles now rise, Figure 18, with the old loops *a* round the shanks of the needles 1 and the new loops *c* disposed around both the shanks of the needles 1 and of the needles 2. As shown in Figure 19 the needles next descend and during the said movement the beards of the needles 2 are pressed by the said presser 6, the result being as shown in Figure 20 that the new loops *c* are cast off the needles 2 and are received on the beards of the needles 1. The needles next further descend in such manner that the new loops *c* are knocked over the needles 1 (Figure 21) while the old loops *a* are still retained in the beards of needles 1. The result of this sequence of operations is that the loops *a* which constitute ground loops are locked by the loops *c* which constitute locking loops and the thread of which encircles the legs of the loops of the ground thread.

It will be appreciated that as shown in Figures 10 to 21, the needles 1 and 2, sinkers 3, knocking over bits 4 and the presser 5 are all actuated in a suitable manner to assist in the formation of the locked loops; the desired motions are effected by mechanism now to be described with particular reference to Figures 1 to 9 and 26. Referring firstly to the needles it should be explained that the motions of both sets of needles to and from the presser are effected through a common mechanism but a separate mechanism is provided for the up and down motions of each set. For this purpose the needle bar 200 (Figures 4, 5 and 26) is provided with a pair of vertical guideways 202 for the reception of a pair of slide members 203 provided on the other needle bar 201. The two bars are shown separately in Figures 4 and 3 and are shown in their operating position (whereat the slide members 203 are guided in the guideways 202) in Figures 5 and 26. The needle bar 201 is also mounted for pivotal movement about

an axis 204 for inspection or repair purposes and it is releasably held in the operative position by means of thumb screws 205 (Figure 26). For the purpose of imparting vertical motion to the needle bar 201 the said bar is provided at its lower end with a pair of rearwardly extending bifurcated lugs 206 which embrace squared spindles 207 freely rotatable in the rear ends 208 of arms 209 fixed to a shaft 300 by bolts 301. The shaft 300 has also fixed to it a rocker arm 10 having a truck 8 at its lower end and this truck bears on a cam A on the main cam shaft Z. The cam A is shaped to effect the desired movements; for example the highest point 212 of the upper half of the cam corresponds to the knocking over position of the needles 1 shown in Figure 12 and the position 211 on the cam corresponds to the landing and pressing position shown in Figure 11; the positions 210 and 213 to 215 also correspond to the Figures 10 and 13 to 15; the position 216 corresponds to the second landing and pressing motion shown in Figure 16; the position 218 corresponds to Figure 18 and is the second knocking over position and the final pressing and knocking over positions are indicated at 219 and 221, corresponding to Figures 19 and 21.

For the purpose of imparting the motions to both sets of needles in a direction to and from the presser, the needle bar 200 has fixed to it an arm 11 to the lower end of which is pivotally connected a hand lever 302; this hand lever is formed with notches 303 cooperating with a peg 304 projecting laterally from an arm 305 fixed to a shaft 306 and also fixed to the shaft 306 there is a truck arm 9 which carries a truck 7 cooperating with a cam B fixed to the main cam shaft Z. This cam B is suitably shaped to effect the desired motions and in the main it is provided with high points at 311 and 312 corresponding to the pressing and knocking over positions shown in Figures 11 and 12 respectively and also positions 316, 319 and 321 corresponding to Figures 16, 19 and 21 respectively which are the final pressing and knock-over positions.

For the purpose of imparting vertical motion to the needle bar 200 the said bar is pivotally connected at its lower end to a pair of rocking arms 12 which are freely mounted on the shaft 300. Also freely mounted on this shaft 300 there is a truck arm 307 which is keyed to the rocker arms 12 by a key 308 (Figure 26) and which carries at its lower end a truck 309 co-operating with a cam C on the main shaft Z. The cam C is provided with three main knocking over positions 412, 417 and 421 corresponding to Figures 12, 17 and 21 respectively. The sinkers 3 are controlled in part by the customary catch bar mechanism (Figures 1, 2 and 6) consisting of arms 19 and 20 connected by links 21 and 22 to truck arms 23 and 24 having trucks 25 and 26 engaging with cams D and E. These cams are suitably shaped and the main positions are indicated by reference numerals 710, 712, 715, 716, 717 and 721 corresponding to the respective Figures 10, 12, 15, 16, 17, 21. The sinkers are advanced by slur cocks in a manner more fully described hereinafter. A hand lever 222 is also provided for the catch bar mechanism. Knocking over bits 4 (Figures 1, 2 and 7) are actuated through arms 27, 223 connecting them to truck arms 28, 224, having trucks 29, 30 controlled by cams F, G; the main positions on these cams are again indicated by reference numerals 511, 512, 517 and 521 and these positions correspond to the respective Figures 11, 12, 17 and 21. There is also provided (Figures 1, 2 and

8) a truck 31 carried by a truck arm 225 for controlling through cam K the jack-springs 32 associated with jacks 33. In addition there is provided quality control mechanism 34 and 35 (see Figures 1 and 2) one for the ground loops and the other for the locking loops. Each mechanism consists of a quality cam H, I, acting on a truck 36, 37 which is carried by a truck arm 38, 39 and the truck arm is fixed on a control shaft 100 to which is also fixed an arm 101, bearing on a rod 103. This rod has fixed to it an extension 226 of the needle bar raising lever 9 so that movement of the needle bar is limited by the quality cam H, I; adjusting means 105, 106 is also provided.

The auxiliary presser or needle deflector 5 is arranged wholly beneath the knocking over bits 4 as shown in Figures 1, 28, 29 and it is constituted by a bar member mounted to swing (under the influence of suitable cams, to be referred to later) about a horizontal axis 231 (Figure 9) from a retired inoperative position (e. g. Figure 10) to an advanced operative position (Figures 13 and 14) in which its margin engages the stems of the lower needles 2 immediately below the knocking over bits 4. Thereby the lower needles 2 are deflected towards the upper needles 1 and their heads (which desirably have a permanent set, as shown, towards the stems of the upper needles) are buried in eyes formed longitudinally in the stems of the upper needles 1. Thus when the two sets of needles are raised in unison (as previously referred to) loops 'a' of the main thread previously encircling the stems of the upper needles 1 above the heads of the lower needles 2 are first brought against the underside of the sinkers 3 (Figure 14) and, being arrested thereby, are transfixed by the lower needles 2.

The margin of the deflector 5 is cut with notches or tricks in which the stems of the lower needles 2 are received immediately below the beards. By this means the heads of the lower needles 2 are correctly registered with the eyes of the upper needles 1. This register is facilitated by making the notches of V-shape (see Figure 30) or shaping their mouths so that their flanks converge, with the result that even if a needle is initially slightly out of register as it enters a notch one of the flanks thereof engages it and deflects it sideways into register. The said auxiliary presser or needle deflector 5 (Figure 1, 2, 9 and 28 to 30) has the requisite motion imparted to it by a cam J, acting on a truck 227 which is carried by a truck arm 228, this truck arm 228 being in turn connected by a link 229 to a rocking arm 230 arranged to rock a rock shaft 231 to which the presser is fixed, and which is mounted on suitable brackets 232. An auxiliary spring 233 is provided for the presser and the presser is adjustably located by bolts 234. The cam J is provided with a low part 613, 614 corresponding to Figures 13, 14. The cams A to J have been illustrated and described as being representative of any suitable arrangement of cams and they are all mounted on a cam shaft Z. In the preferred arrangement illustrated however (which is referred to in co-pending application Serial Number 43,834), a single cam is substituted for each pair of cams and each of these single cams is so designed as to effect the necessary movements for the ground loops by one part of its periphery and to effect the necessary movements for the locking loops by another part of its periphery; in each of Figures 3 to 9 the upper half of the cam is for the ground loops and the lower half is for the locking loops.

If it is desired at any time to knit plain fabric e. g. for the welt of a stocking, this is readily accomplished by additional cams associated with the cams A to I (and indicated in broken lines and by references P1 to P11 in Figure 2) and onto which the trucks may be shogged; these additional cams are shaped to produce two successive plain stitch motions corresponding to Figures 10 to 12 and in the main for the purpose the lower halves of the additional cams will be the same as the upper halves thereof as indicated in broken lines in Figures 2 and 3 to 7.

If it is desired to continue employing the double draw mechanism and two main carriers when making plain fabric, either the cam shaft Z is shogged or the appropriate trucks are shogged to bring the appropriate plain cams P1 to P11 into action. Additionally, instead of utilising both the carriers 156 and 158, it is preferred to idle the locking carrier and to introduce a new main carrier in its place. For this purpose a third carrier rod 400 (Figures 1, 2, 22, 22a) and carrier 401 is provided, the rod 400 being reciprocated in the same manner as the bars 150, 151; this carrier 401 together with the locking carrier 156, or 158 are each arranged to be rendered operative or idle at the appropriate time by any suitable means such as a hand operated selecting catch or the like indicated at 402 which is fixed to the machine frame and is arranged to be coupled to or disconnected from the carrier 401 to prevent or permit movement thereof as and when desired. If desired, the main carrier employed for locked fabric may be also idled (by similar means to that above described) when making plain fabric and a fourth carrier (with associated rod and selecting catch or the like) may be employed in its stead.

Alternatively, if it is desired only to employ one carrier and a single draw for plain fabric, the cam shaft Z (or the appropriate trucks) is shogged as before and the locking carrier is idled by the means above referred to. Additionally either the bolt 50 or 50' (hereinafter referred to) is rendered inoperative by any suitable means; for example the appropriate bolt is withdrawn out of the path of the blocks 54, 54' and a hand operated catch or the like indicated at 403 in Figures 1, 2, 22 to 25 is employed to maintain the bolt 50 or 50' in its retracted position.

It is to be understood that whereas only hand operated mechanism has been referred to for selecting the carriers and the bolts, these operations may be readily carried out in a semi-automatic or completely automatic manner by any known or suitable type of selecting mechanism operated e. g. from the main pattern chain of the machine.

Fashioning cams shown in broken lines at F1 to F11 are also preferably provided, one associated with each cam A to I and onto which the trucks may be shogged (or which are moved under the trucks by shogging the cam shaft) to permit fashioning to be carried out in the customary manner. Additional cams F12 are provided controlling customary fashioning points through the intermediary of customary mechanism.

Each truck may be moved onto any one of the three cams associated with it by any suitable means such as by shogging rods controlled by the customary main pattern chain. Alternatively, the cam shaft may be shogged into any one of three alternative positions by any suitable means such as by providing a cam on the cam shaft 75 which is laterally stepped on both faces and has

a truck engaging each face, the arrangement being such that the trucks are controlled by the customary pattern chain to engage appropriate steps of the cam so as to shog the cam shaft for the appropriate distance in either direction. The aforesaid shogging mechanism is known in the art and needs no further description or illustration herein.

In the machine illustrated (and later to be described more fully) the slur cock tie bar is provided with slur cocks which are spaced apart by an amount at least equal to the width of the division so that only one slur cock operates on the jacks at a time. The arrangement of the machine is such that this tie bar is capable of at least twice the normal traverse thereby permitting it to be traversed in either direction firstly by an amount sufficient to cause one slur cock to operate all the jacks and subsequently by a like amount sufficient to cause a following slur cock to operate all the jacks. Thereafter, of course, the slur cock tie bar is given a like two-stage movement in the opposite direction. For the purpose of illustration, the machine shown is a single division machine and consequently only two slur cocks 49a, 49b are provided. In the case of a multi-division machine there is one more slur cock than there are divisions and these slur cocks are spaced apart by an amount equal to the distance between the centres of successive divisions as indicated in Figure 27.

Referring again to the drawings and particularly to Figures 22 to 25 there are provided two Coulier or draw mechanisms 40, 41 moving in opposite directions through the intermediary of bevel gearing 42, and the construction of each draw mechanism may follow known lines and may for example consist of a draw lever 43, 44 swung to and fro by a draw cam 45, 46. Each draw lever is connected to a driver 47, 48 and mechanism indicated by the reference numerals 47a, 48a is provided for connecting and disconnecting these drivers 47, 48 to and from a tie bar 49 carrying the slur cocks 49a, 49b. The said mechanisms 47a, 48a are substantially identical and for the purpose of description the mechanism 47a is shown in enlarged detail in Figures 24 and 25. Each mechanism incorporates a slidable bolt 50, 50' carried by the driver 47, 48. This bolt is biased by springs 51, 51' into a projected attitude whereat a ball bearing truck 52, 52' carried by it is located in the path of a cleft 53, 53' formed in a block 54, 54'. The operation in brief (and described more fully later on) is that block 54, 54' is carried by the tie bar 49 in such manner that when the tie bar is traversed say to the left into the position shown in Figure 24 and the bolt 50 is projected, the truck 52 rides along a ramp 55 carried by the block 54 to guide the truck into the cleft 53. Similarly when the tie bar travels to the right and the bolt 54' is projected the truck 52' rides along a ramp 55' (which is oppositely directed to the ramp 55) to guide the truck into the cleft 53'. Means are provided for moving the bolts 50, 50' out of the path of the clefts 53, 53' at appropriate times and said means preferably consists of cams 66, 66' fixed on a cam bar 67 which is shogged periodically first in one direction and then in another. The cams 66, 66' are arranged to withdraw the appropriate bolt 50, 50' by engagement of the cams with ball bearing trucks 50a, 50b, one on each bolt. The cam bar may be shogged by an abutment on the tie bar striking a part of the cam bar at the

end of each double traverse or by a rotating cam, the speed of which is one quarter of that of the main cam shaft. Preferably however, as shown in the drawings, said means consists of hydraulic mechanism. This mechanism as shown in Figure 22 consists of a motor driven pump 76 for setting up pressure in a supply line 77 through a pressure gauge 78 to a hydraulic jack 79 through a two-way valve 60. From this valve there are two lines, one to each end of the jack and there is a valve rod 260 arranged by its end-wise movement in opposite directions to open either one of these lines to the pressure in the pressure line. The valve rod 260 is actuated through the medium of a slidable rod 261 on which there are spaced abutments 61, 62 and these abutments 61, 62 are located in the path of an actuating member 63 carried by a block 64 fixed to the tie bar 49. The arrangement is such that at the end of each double traverse of the tie bar the rod 261 is shogged in opposite directions and the effect of this is for the piston 262 of the jack 79 to be projected or retracted. The end of the piston 262 is arranged to engage an adjustable abutment 65 carried by the cam bar 67 and it thus follows that at the end of each double traverse the cam bar is shogged to actuate the appropriate bolts.

More specifically the arrangement is such that a complete cycle of movements is effected as follows. Assuming that both the slur cocks are located at the left hand end of the division, the drivers 47, 48 are at their widest distance apart; the bolt 50 of the driver 47 is engaged with the cleft 53 and the bolt 50' of the driver 48 is disengaged from the cleft 53' by the cam 66'; the cam bar is located towards the left hand end of the machine. For the next stage the drivers move towards each other and because the driver 47 only is connected to the tie bar by the bolt 50 the slur cocks move to the right and the leading slur cock passes across the division of needles. At the end of the draw the truck 50a engages the cam 66 so that the bolt 50 is withdrawn; the cam 66' is out of the path of the bolt 50' which therefore automatically engages the cleft 53'. Subsequent movement of the drivers in an outward direction results in the tie bar moving a further distance to the right because now only the driver 48 is connected to the tie bar and therefore the trailing slur cock now passes across the division from left to right. At the end of this traverse no change is made to the bolts 50, 50' with the result that at the next stage (i. e. when the drivers move inwards) the driver 48 only is operative by virtue of its connection with the tie bar and therefore the tie bar and slur cocks move to the left. At the end of the previous draw to the right, however, the control rod is shogged to the right by the projection 63, the result being that the cam bar is also shogged to the right. Therefore, as shown in Figure 23, at the end of the aforesaid draw to the left the cam 66' breaks the connection of the bolt 50' with the driver 48 and the bolt 50 automatically connects with the driver 47; consequently for the next stage the tie bar and the slur cocks move a further distance to the left to their original position; at this position the control rod 261 is shogged to the left so that the parts are then suitably arranged for the cycle of operations to be repeated.

In a multi-division machine the first stage of

movement results in each slur cock (other than the trailing end one) traversing over a division, and in the second stage of movement each slur cock (other than the leading end one) traverses over the next division so that each division is traversed by the two slur cocks.

During the first stage of movement in either direction the carrier for the ground thread is traversed across the division of needles and during the second stage of traverse in that direction the carrier for the locking thread is traversed across the division. Naturally, there is an interval between these two carrier traverses, during which the other motions of the knitting cycles are effected. Any suitable carrier driving mechanism may be provided for producing these carrier movements. It will be appreciated however, that the ground thread for any division traverses in each direction with the slur cock that for the time being is the leading slur cock for that division.

In one arrangement of carriers there are provided two carrier bars 150 and 151 (Figures 1, 2 and 22 and 23). These carrier bars are mounted to slide in spaced brackets 152 and they are reciprocated to and fro by a driving member 153 part of which engages in a slot 154 in each guidebar and which is fixed to the block 64 fixed to the tie bar 49. This tie bar is reciprocated to the extent of the two draws to and fro and therefore the guidebars are also reciprocated in a like manner. One of these guidebars has a thread guide 156 connected to it through the medium of a friction box 157 of any convenient type and the other guidebar has a thread guide 158 connected to it also through the medium of a friction box 159. This box has pivotally connected to it a pair of catch levers 160 each having an enlarged head 161 arranged to engage at appropriate times behind the hooks of pivoted detents 162. These detents are spring biased downwardly and pivoted catch levers 160 are spring biased in such manner as to urge their enlarged heads downwardly. These enlarged heads, however, normally rest on the upper surface of the guidebar and they are arranged to co-operate at appropriate times with recesses 163 respectively, one in each side of the guidebar and at suitably spaced intervals in the length thereof. In operation, assuming that both thread guides 156 and 158 are in abutting engagement (at one end of their traverse) with one of the brackets 152, one of the enlarged heads 161 will be in engagement with the detent 162 associated with the said bracket, and the recess 163 with which said head is arranged to co-operate will be situated approximately one needle division width away from the said bracket and in a direction away from the division over which the thread guides 156 and 158 are intended to be traversed. When the carrier bars are traversed across the needle division this results in the thread guide 156 being carried across the division while the carrier 158 remains held by the detent 162. When, however, the thread guide 156 reaches the end of its travel the recess 163 becomes positioned beneath the head 161 of the said catch 160 whereupon the catch rocks under the influence of its spring thereby releasing it from engagement with the detent 162. Upon further movement of the guidebars therefore in the same direction the thread guide 158 is carried across the division whereas the thread guide 156 is held stationary by one of the brackets 152. When the carrier 158 reaches the end of its travel the pivoted

catch 161 which has previously been idle now engages the detent 162 associated with the last mentioned bracket. Therefore when the carrier bars reverse their direction of travel the thread guide 158 is held stationary by the said detent 162 while the thread guide 156 is traversed across the division and by the time this carrier 156 reaches the end of its travel the second recess 163 in the guidebar 150 becomes located beneath the head of the last mentioned pivoted catch 161 thereby permitting the catch to be released from the detent 162; the result is that for the remaining traverse of the carrier bars the thread guide 156 remains stationary abutting against the first mentioned bracket 152 while the thread guide 158 is traversed across the needle division by the carrier bar 150. In this manner it will be seen that the thread guides 156 and 158 are carried across the needle division one after the other and the carrier to be first moved from one end of the division to the other is the first to be moved in the reverse direction. It is to be understood that the particular carrier control described above may be varied in many ways, for example, there may be provided an additional draw mechanism for traversing the block 64 which for the said purpose may be mounted on a separate friction bar and fixed to a separate tie bar. It is also to be understood that the invention is not restricted to the provision of duplicate draw levers, draw cams and associated mechanism as shown in the drawings, as there may be provided only one of such draw mechanism; in this event there may be provided suitable means such as racks and a pinion or an endless chain for converting opposite movements of the draw lever into the desired double movements in the same direction of the slur cocks.

The relative amounts of ground thread and locking thread fed per course of stitches may be varied for particular requirements but in one specific example for the production of ladies' silk stockings the ratio of the ground thread to the locking thread is 37 to 38; that is to say, that to every 37 inches of ground thread there are 38 inches of locking thread irrespective of the count or diameter of the yarn.

In this specification the word "division" means, where the context so permits, that part of the machine associated with one width of needles.

We claim:

1. In a straight bar knitting machine for the production of knitted goods by steps which include drawing a locking loop through a normal loop of a preceding course of needle loops a plurality of times by means of bearded needles thereby producing looping parts in the limbs of the locking loops which encircle the limbs of said normal loop, said machine having an upper and a lower set of bearded needles whereof those of the lower set are located immediately to the rear of but slightly lower than those of the upper set and the needles of the upper sets having eyes for the reception of the heads of the needles of the lower set, a knocking over bar equipped with knocking over bits, and a press edge for operating on the beards of the needles; the provision of a needle - deflector additional to the press edge and the knocking over bar, for producing such needle deflection as will bury the heads of the lower needles in the eyes of the upper needles which needle-deflector is disposed beneath the knocking-over bits.

2. A machine according to claim 1, wherein the needle deflector is arranged wholly beneath

said knocking-over bits and is constituted by a member which is mounted to swing about a horizontal axis from a retired inoperative position to an advanced operative position in which its margin engages the stems of the lower needles immediately below the knocking-over bits, and having means for effecting such movement.

3. A machine according to claim 1, having means mounting the deflector for rocking movement about an axis parallel to the needle line; a main cam shaft, and a disc cam on the latter and link and lever mechanism for rocking the deflector into and out of deflecting position.

4. In a straight bar knitting machine for the production of knitted goods by steps which include drawing a locking loop through a normal loop of a preceding course of needle loops a plurality of times by means of bearded needles thereby producing looping parts in the limbs of the locking loops which encircle the limbs of said normal loop, said machine having an upper and a lower set of bearded needles whereof those of the lower set are located immediately to the rear of but slightly lower than those of the upper set and the needles of the upper sets having eyes for the reception of the heads of the needles of the lower set, a knocking over bar equipped with knocking over bits, and a press edge for operating on the beards of the needles; the provision of a needle-deflector additional to the press edge and the knocking over bar, for producing such needle deflection as will bury the heads of the lower needles in the eyes of the upper needles, and means mounting the deflector for movement into and out of a deflecting position in which it engages the shanks of the lower needles.

5. In a straight bar knitting machine, the combination of two sets of bearded needles, viz. an upper set and a lower set located at the beard side of the upper set, said needles of the upper set having eyes for the reception of the heads of the needles of the lower sets, means for feeding yarn to the needles for formation into needle loops, a knocking over bar equipped with knocking over bits, sinkers, a press edge for pressing the beards of both sets of needles, and needle-operating means for causing the needles of the upper set to produce a row of needle loops and to pass them through a previous course, the needles of the lower set to penetrate said loops while still on the needles of the upper set and to draw locking loops through them, and the needles to the upper set to cast off said locking loops while retaining the loops of said row, the combination of a needle deflector for engaging the stems of the lower set of needles at a location below the knocking over bits and for deflecting said needles to bury their heads in the eyes of the upper needles, means mounting said deflector for movement to and from deflecting position, and operating mechanism for moving it to deflecting position, after the formation of said row of loops, to deflect the heads of the needles of the lower set and to assist said needles to penetrate the loops.

6. In a straight bar knitting machine for the production of knitted goods by steps which include drawing a locking loop through a normal loop of a preceding course of needle loops a plurality of times by means of bearded needles

thereby producing looping parts in the limbs of the locking loops which encircle the limbs of said normal loop, said machine having an upper and a lower set of bearded needles whereof those of the lower set are located immediately to the rear of but slightly lower than those of the upper set and the needles of the upper sets having eyes for the reception of the heads of the needles of the lower set, a knocking over bar equipped with knocking over bits, and a press edge for operating on the beards of the needles; the provision of a needle-deflector additional to the press edge and the knocking over bar, for producing such needle deflection as will bury the heads of the lower needles in the eyes of the upper needles, which deflector is located below the knocking over bits and at the bearded side of the lower set of needles to engage and deflect said lower set of needles.

7. In a straight bar knitting machine for the production of knitted goods by steps which include drawing a locking loop through a normal loop of a preceding course of needle loops a plurality of times by means of bearded needles thereby producing looping parts in the limbs of the locking loops which encircle the limbs of said normal loop, said machine having an upper and a lower set of bearded needles whereof those of the lower set are located immediately to the rear of but slightly lower than those of the upper set and the needles of the upper sets having eyes for the reception of the heads of the needles of the lower set, a knocking over bar equipped with knocking over bits, and a press edge for operating on the beards of the needles; the provision of a needle-deflector additional to the press edge and the knocking over bar, for producing such needle deflection as will bury the heads of the lower needles in the eyes of the upper needles, which deflector is located below the knocking over bits and at the bearded side of the lower set of needles to engage and deflect said lower set of needles.

8. A machine according to claim 7, having a main cam shaft, a disc cam on said shaft, and link and lever mechanism for rocking the deflector into and out of deflecting position, means for mounting the deflector for rocking movement about an axis parallel to the needle line, and means for adjusting the attitude of the deflector relatively to said cam.
